UNITED STATES PATENT OFFICE.

JOHN F. LEVAN, OF ELKHART, INDIANA, ASSIGNOR TO THE ADLAKE COMPANY, OF CHICAGO, ILLINOIS, A CORPORATION OF ILLINOIS.

SASH GUIDE.

Application filed May 12, 1927. Serial No. 190,709.

This invention has to do with sash guides of the detachable side wall type developed by me and disclosed in my pending application, Serial No. 106,841 filed May 5, 1926.

5 The primary object of the invention is to provide an improved sash guide of the type described, in which the detachable side wall is caused to bear resiliently against the associated sash by a spring which acts against

10 such side wall.

Other objects and advantages will be evident to those skilled in the art upon a full understanding of the improved sash guide.

15 Three different forms of the invention are presented herein by way of illustration, but it will be appreciated, of course, that the invention may be embodied in other forms coming equally within the comprehensive scope of the claims.

20 In the drawing:

Fig. 1 is a fragmentary side view of a sash associated with the improved guide;

Fig. 2 is a transverse section through the guide, with the sash removed;

25 Fig. 3 is a similar section, with the sash in position;

Fig. 4 is a perspective view of the retaining strip which constitutes the detachable side wall of the guide;

30 Fig. 5 is a transverse section through a double sash guide, showing the invention in a slightly modified form.

Fig. 6 is a transverse section through 35 a guide embodying another slightly modified form of the invention;

Fig. 7 is a similar section, showing the sash in position; and

Fig. 8 is a perspective view of the retaining strip shown in Figs. 6 and 7.

40 The sash guide illustrated in Figs. 1 to 4 inclusive consists of a fixed strip 10 and a detachable strip 11. The strip 10 is adapted to be attached to the jamb of a window frame by screws or other suitable means,

45 and is provided, at one side, with a groove 12, and, at the other side, with a fixed side wall 13. If it is desired to have a guide in

50 which the sash may be removed from either side, the fixed side wall 13 may be dispensed with, and another groove, corresponding to

the groove 12, may be provided at that side of the strip in lieu of the fixed side wall.

The strip 10 is made of sheet metal, and is bent in such a way as to form the groove 12, the fixed side wall 13 and an intervening

web 14. The strip obviously may be bent in a great many other different ways to provide the portions described. The strip 11 constitutes a removable side wall opposite the fixed side wall 13, and is seated within 60 the groove 12. The portion of the strip 11 within the groove is provided with a spring strip 15, which is soldered or secured in any suitable fashion to the inner edge of the strip and extends at an angle from the same. 65

When the strip 11 is seated in the groove 12 in the strip 10, without any sash being in association with the guide, it will assume the canted position shown in Fig. 2, but when a sash 16 is in place in the guide, with one 70 side wall 17 of the sash against the fixed side wall 13 of the strip 10, the strip 11, upon being inserted in the groove in the strip, will be held out by the side wall 18 of the sash in a position generally parallel to the 75 fixed side wall 13 of the strip 10, as shown in Fig. 3, and will be pressed resiliently against the side wall 18 of the sash by the spring action of the strip 15.

The groove 12 is preferably a little V- 80 shaped in cross section, in order to provide ample space into which the portion of the strip 11 within the groove may move as the projecting portion of the strip opposite the fixed side wall 13 approaches that side wall 85 in moving into engagement with the side wall 18 of the sash.

The strip 11 may be held in position in the groove 12 by any suitable means. Preferably it is held in position by providing 90 bayonet slots 19 at intervals in the strip, which slots are adapted to interlock with rivets or screws 20 which extend at corresponding intervals across the groove. After the strip 11 has been shifted into interlocked 95 engagement with the members 20, the strip may be held against further movement by means of a screw 21 which extends across the groove and passes through an aperture 22 in the strip. 100

The strip 11 may be provided, intermediate its edges, with an offsetting portion 23, which, when the strip is seated in the groove 12, practically covers the open face of the groove. 105

The sash guide illustrated in Fig. 5 is of double as distinguished from single construction, and is designed to receive two sashes 24 and hold the same in spaced relation to each other—which is the sash ar- 110

arrangement generally employed in railway car window construction. The portion of the guide cooperating with each sash is provided with two grooves 25, one at each side 5 of the sash, and such grooves are adapted to receive detachable retaining strips 26 which permit either sash to be removed in either direction. The two outside grooves in the guide are produced by bending the margins 27 of the fixed strip 28, and the two inside grooves are produced by attaching a supplemental strip 29 of U-shaped cross section to the intermediate portion of the strip 28.

15 The strips 26 are provided with spring strips 30, and the strips 26 are bent upon themselves in such a way as to clamp the strips 30 securely in position without the necessity of using solder or other securing 20 means. The strips 26 are fulcrumed against the sides of the grooves 25 at 31, and the spring strips 30 press against the side walls of the grooves adjacent the bottoms thereof and tend to press the outer edges of the 25 strips 26 resiliently against the side walls of the sashes. At those points where the strips 26 fulcrum against the side walls of the grooves, the side walls may be slightly bowed in order to interlock frictionally with 30 correspondingly bowed portions of the strips 26, thereby dispensing with the necessity of using any additional positioning means for the strips.

In the sash guide illustrated in Figs. 6 to 35 8 inclusive, the spring strip 32, instead of being soldered to the removable strip 33 as shown in Figs. 1 to 4 inclusive, is clamped against a portion of the same in a locking groove 34 of a reversely bent and correspondingly grooved flange 35 along the outer edge of the strip. From the groove 34 the strip 32 extends inwardly to the inner edge of the strip 33, where it is folded back about such edge and projects at an angle to the 45 strip 33 in spring-pressed engagement with the opposing side wall of the groove 36 in the fixed strip 37.

In all three forms of the invention described, the improved spring mounting of 50 the detachable side wall or walls of the guide serves to hold the sash resiliently in position in the guide, and serves to afford a weather-proof closure throughout the length of the same, both along the line of contact of the 55 detachable side wall with the sash and along the line of contact of the spring strip with the side wall of the groove. When a guide embodying the invention is employed as a sash mounting, removal of the sash from the 60 guide for any reason, such as re-glazing or repairing, is an exceedingly simple matter.

I claim:

1. In a sash guide, a fixed strip having a 65 groove, a detachable strip seated in the groove, and means acting against the detach-

able strip to press the same resiliently against a sash in the guide.

2. In a sash guide, a fixed strip having a groove, a detachable strip seated in the groove, and means positioned in the groove 70 and acting against the detachable strip to press the same resiliently against a sash in the guide.

3. In a sash guide, a fixed strip having a groove, a detachable strip seated in the 75 groove, and a spring strip acting against the detachable strip to press the same resiliently against a sash in the guide.

4. A sash guide having a removable side wall, and a spring strip associated with 80 said side wall throughout substantially the entire length of the same for pressing said side wall against a sash in the guide.

5. In a sash guide, a fixed strip having a 85 groove, a detachable strip seated in the groove, and a spring strip secured to one of said strips and bearing against the other for pressing the detachable strip resiliently against a sash in the guide.

6. In a sash guide, a fixed strip having a groove adjacent one side thereof, a detachable strip seated in the groove, and a spring strip secured to the detachable strip and bearing against one side of the groove in the fixed strip for pressing the detachable 90 strip resiliently against a sash in the guide.

7. In a sash guide, a fixed strip having 100 grooves adjacent the sides thereof, detachable strips seated in the grooves, and means acting against one or both of said strips for causing a sash in the guide to be clamped resiliently between the detachable strips.

8. In a sash guide, a detachable strip having a reversely bent portion, and a spring strip clamped against the detachable strip 105 by the reversely bent portion of the latter.

9. In a sash guide, a detachable strip having a grooved portion and a reversely bent portion, and a spring strip having a 110 grooved portion which is clamped within the grooved portion of the detachable strip by the reversely bent portion of the latter.

10. In a sash guide, a fixed strip having a groove, and a detachable strip seated in the groove, said detachable strip being offset 115 adjacent the opening in the groove whereby to provide a closure for such opening when the detachable strip is in position.

11. In a sash guide, a fixed strip having a groove, a detachable strip seated in the 120 groove, and means acting against the detachable strip to press the same resiliently against a sash in the guide, said means also tending to prevent removal of the detachable strip from the groove.

12. A sash guide having a removable side wall, said side wall being so constructed as to press resiliently against a sash positioned in the guide, and being so arranged as to permit when removed a sash to be placed in 125

or removed from the guide in a direction is adapted to bear, which portion is unobstructed laterally in both directions 15 laterally of the same.

13. In a sash guide, a fixed strip having a portion against which the edge of a sash is adapted to bear, which portion is unobstructed laterally whereby to permit a sash to be shifted laterally into or out of opposition with the same, and two detachable strips at the opposite sides of said portion adapted to clamp the edge of a sash resiliently between the same 20 and prevent the sash from being shifted laterally.

In testimony whereof I have hereunto subscribed my name.

JOHN F. LEVAN.

14. In a sash guide, a fixed strip having a portion against which the edge of a sash
